[57] CLAIM

The ornamental design for a handle for a shoe-polishing accessory or the like, as shown.

DESCRIPTION

FIG. 1 is a right-side elevational view of a handle for a shoe-polishing accessory or the like showing our new design;

FIG. 2 is a front elevational view thereof;

FIG. 3 is a rear elevational view thereof;

FIG. 4 is a top plan view thereof;

FIG. 5 is a left-side elevational view thereof; and

FIG. 6 is a bottom plan view thereof.

FIG. 4

FIG. 6
